Primary Examiner — John R Yeh

(74) Attorney, Agent, or Firm — Suzanne Kikel, Patent Agent

(57) **CLAIM**

The ornamental design for a car washing glove, as shown and described.

DESCRIPTION

FIG. 1 is a rear view of my new design for a car washing glove with the strap in an open configuration;

FIG. 2 is a front view thereof;

FIG. 3 is a right side view of FIG. 2;

FIG. 4 is a left side view of FIG. 2; and,

FIG. 5 is a bottom view of FIG. 2.

The broken lines shown in the drawings depict portions of the car washing glove that form no part of the claimed design.
